ABSTRACT: A packaging protector comprising an annular divider member or partition of resilient material, such as polyethylene, for nesting within a frangible dish-shaped or bowllike piece of ware a separate complementing and frangible cover in an impact-absorbing or cushioned spaced-apart relationship with the piece of ware as well as providing for impact absorbing or cushioning between the walls of a package packed in the carton of the package for shipping or storage purposes.

AGENT

PACKAGING PROTECTOR

BACKGROUND OF THE INVENTION

There is disclosed in U.S. Pat. No. 3,113,667, issued Dec. 10, 1963 to Eugene J. Knapp et al., a frangible ware package including an impact-absorbing partition or ring member 12 made of a substantially rigid yet compressible foamed plastic material such as foamed polystyrene and used for the same purpose as the packaging protector or partition of the present invention. However, as is well known in the art, a ring member such as 12 shown in said patent, because of a substantial lack of resiliency and elasticity must have relatively thick impact-absorbing walls and, therefore, requires the ware package to be larger, that is, to have more packaging space than when a packaging protector such as disclosed in the present application is employed. The saving in packaging space in each respective ware package with which a packaging protector of the present invention is employed will possibly not be considered too substantial but, when the space saved in the storing or shipping of a relatively large number of the ware packages is considered, as well as the lesser weight of such a number of the smaller packages, relatively substantial economic savings can be anticipated or foreseen. This will be readily apparent to those skilled in the packaging art.

SUMMARY OF THE INVENTION

In practicing the invention disclosed, there is provided a packaging protector comprising an annular partition or divider member of a resilient material, such as polyethylene or other elastomeric material, and whose lower surface is intended to rest on the top surface of the rim of a frangible dish-shaped or bowllike piece of ware while a wall depending from the inner periphery of said annular member fits in the inner periphery of said rim, preferably with the outer surface of such wall contacting said surface of said inner periphery in a relatively snug relationship therewith. A separate frangible and complementing cover is intended to nest in an inverted attitude within the open end of said piece of ware with the normally upper surface of an outer annular flange portion of such cover resting on the upper surface of said annular partition or divider member opposite said top surface of said rim of said piece of ware. The annular dividing member further includes on the outer periphery thereof a plurality of outwardly extending or projecting cushioning or impact-absorbing tab, lug or ear portions which are intended to contact the inner surfaces of the sidewalls of a carton of a ware package for impact-absorbing or cushioning between said sidewalls and the outer peripheries of the rims of said piece of ware and its complementing cover packed in said carton.

BRIEF DESCRIPTION OF THE DRAWINGS

In the drawings:

FIG. 1 is a top plan view of the packaging protector embodying the invention and illustrating its use in protecting a dish-shaped or bowllike piece of ware packed in a shipping package;

FIG. 2 is an elevational cross-sectional view taken generally along line 2-2 of FIG. 1;

FIG. 3 is a fragmental cross-sectional view in elevation taken generally along line 3-3 of FIG. 1;

FIG. 4 comprises an enlarged cross-sectional view in elevation taken generally along line 4-4 of FIG. 1 and with portions of the packaging protector and portions of the shipping carton omitted for purposes of simplification of the drawing; and

FIG. 5 comprises a fragmental bottom plan view taken generally along line 5-5 of FIG. 4.

Similar reference characters refer to similar parts in each of the FIGS. of the drawings.

PREFERRED EMBODIMENT OF THE INVENTION

Referring to the drawings in detail, there is shown a package 10 including an outer carton 11, the packaging protector embodying the present invention and comprising an annular partition or a divider member 12 of a resilient material, such as polystyrene or other elastomeric material, a dish-shaped or bowllike frangible piece of ware such as 13 having generally upright or upwardly extending sidewalls such as 13a terminating in a rim 13b bordering and defining the usual opening leading into the interior of said piece of ware, and a frangible complementing cover 14 (FIG. 2) nesting in an inverted position in the upper open end of the piece of ware 13 with a flat and relatively thin and narrow annular main portion 12m of partition or divider member 12 disposed between said ware and its cover with the lower surface of said thin annular main portion 12m of the divider member disposed adjacent the top surface of rim 13b of ware 13. The normally upper surface of an outer peripheral region or an annular flange portion 22 extending outwardly from a normally depending and low annular wall portion 21 of cover 14 is shown disposed adjacent the upper surface of the annular main portion 12m of partition or divider member 12. A relatively thin wall 12h depends from the inner periphery of main portion 12m of annular member 12 and preferably tapers or graduates in thickness in an inner direction and towards the lower edge thereof. Wall 12h of member 12 fits in the inner periphery of rim 13b of ware 13 with the outer surface of said wall disposed adjacent the surface of the inner periphery of said rim and, preferably, but not necessarily, contacting such latter surface in a snug relationship therewith. The similarity between items 10, 11, 13 and 14 shown in the drawings of the present application and the correspondingly designated items shown in the drawings of the previously cited patent to Knapp et al. will be readily apparent from a brief comparison of such drawings. However, the partition or divider member 12 of the present invention is substantially different from the corresponding member 12 of Knapp et al.

The packaging protector of the present invention and comprising partition or divider member 12 further includes first and second pairs of diametrically opposite impact-absorbing or cushioning, and generally hollow, ear, lug or tab portions such as 12a each of which extends or projects outwardly from the outer periphery of the annular main portion 12m of member 12, and each of which embodies a pair of upper cavities such as 12b and 12c, and a pair of lower cavities such as 12f and 12g. The boundaries of cavities 12b and 12c are defined by relatively thin inner and outer walls such as 12d and 12i, respectively, (FIGS. 1 and 4) and a relatively thin center dividing wall such as 12n (FIG. 1). The outside surface of each of the walls such as 12d conforms in configuration to a part of the outer peripheral surface of flange portion 22 of cover 14 and all of the walls such as 12d, 12i and 12n extend upwardly from the plane of the upper surface of said annular main portion 12m of divider member 12. The thicknesses of said walls are somewhat exaggerated in the drawings for purposes of clarity, and for purposes of crosshatching in the cross-sectional views.

Similarly, the boundaries of cavities 12f and 12g are defined by center dividing walls such as 12p (FIG. 5), inner walls such as 12k, and the previously mentioned outer walls such as 12i which are common to both the upper and lower cavities. The outside surface of each of the walls such as 12k conforms in configuration to a part of the outer peripheral surface of rim 13b of ware 13 and all of the walls such as 12k and 12p, and said common outer walls such as 12i, extend downwardly from the plane of the lower surface of said annular main portion 12m of divider member 12. The thicknesses of such walls, as well as the thickness of previously discussed depending annular inner wall 12h, are also somewhat exaggerated in cross-sectional views, FIGS. 2, 3 and 4 of the drawings for crosshatching purposes. The downwardly extending walls such as 12k of ear, lug or tab portions 12a, in conjunction with de-

pending wall 12*h*, provide channels such as 12*e* (FIGS. 4 and 5) in which portions of the rim 13*b* of a piece of ware such as 13 fit, preferably in a relatively snug relationship with the walls defining the boundaries of the channels such as 12*e*. The outwardly extending or projecting ear, lug or tab portions such as 12*a* of divider member or partition 12 project or extend from locations on the outer periphery of the annular main portion 12*m* of member 12 such that, when ware 13 and cover 14 are packed in a carton such as 11 of a package such as 10, the outer surfaces of the outer walls such as 12*i* of the tab portions such as 12*a* are disposed adjacent the inner surfaces of the sidewalls of said carton as illustrated in FIG. 1 and with said surfaces preferably, but not necessarily, contacting each other in a relatively snug relationship.

The drawings having been discussed in detail, a brief description of the use of the package protector comprising partition or divider member 12 will now be set forth.

As previously mentioned, the shipping package 10 comprising a carton such as 11, and shown in FIGS. 1 and 2 of the drawings of the present application, is similar to package 10 comprising carton 11 of FIGS. 1 and 2 of the cited Knapp et al. patent except that carton 11 of the present application is square in configuration rather than somewhat oblong as in said patent. Furthermore, the piece of ware 13 and its complementing cover 14 of the present application, as well as the enclosing top wall 15 of carton 11, which is broken away in FIG. 1 of the present application to better illustrate the attitude of ware 13 when packed in carton 11, are similar to the correspondingly designated items of Knapp et al. Ware 13 is also shown as having a pair of outwardly extending handle portions 18 formed integrally with the outer periphery of rim 13*b* of the ware at locations opposite each other along said rim and similarly to the corresponding handle portions 18 of the cited Knapp et al. patent. However, as illustrated in FIG. 1 of the present application, ware 13 is shown placed within carton 11 with the extending handle portions such as 18 disposed in a pair of opposite corner regions of the carton, that is, with said handle portions extending toward a pair of opposite corners of carton 11. This arrangement permits the square configuration of carton 11 rather than the oblong configuration of carton 11 of the Knapp et al. patent and permits a further reduction in the packaging space required in a ware package such as 10.

As previously mentioned, in using a packaging protector comprising an annular partition or divider member such as 12, the dish-shaped or bowllike piece of ware such as 13 is placed in a carton such as 11 as shown in FIGS. 1 and 2 of the drawings, and divider member 12 is placed over rim 13*b* of ware 13 with the lower surface of the annular main portion 12*m* of the divider member disposed adjacent the top surface of said rim so that the depending annular wall 12*h* of member 12 extends into the opening into ware 13 (FIGS. 2 and 3) and so that rim 13*b* extends into channels 12*e* provided in said divider member. Carton 11 is of a size selected so that the outer surfaces of the outer walls such as 12*i* of the extending ear, lug or tab portions such as 12*a* of divider member 12 are adjacent to or contact the inner surfaces of the sidewalls of carton 11. Cover 14 is then placed in an inverted attitude within divider member 12 and in a nesting relationship within the opening of ware 13 with the upper surface of flange portion 22 of cover 14 disposed adjacent the upper surface of the annular main portion 12*m* of divider member 12 as shown in FIG. 2. Wall 12*h* of member 12 is preferably but not necessarily, of a thickness such that cover 14 fits within member 12 with the outer surface of wall portion 21 of cover 14 contacting the inner surface of wall 12*h* of member 12 in a relatively snug relationship therewith. The extending ear, lug or tab portions 12*a* of member 12 provide for cushioning or impact energy absorbing between the sidewalls of carton 11 of package 10 and the rims of the piece of ware 13 and of annular flange portion 22 of cover 14, while the annular main portion 12*m* of member 12 provides for cushioning between the upper surface of rim 13*b* of ware 13 and the normally upper surface of said flange portion 22 of cover 14.

It is pointed out that annular main portion 12*m* is shown in the drawings as having a planar configuration corresponding to that of rim 13*b* of the piece of ware 13 and, if the rim of the piece of ware with which a divider member such as 12 is to be used has a configuration other than that illustrated for ware 13, such as a circular configuration for example, the annular main portion such as 12*m* of the divider member such as 12 would, of course, correspond to such configuration. It is further pointed out that divider members such as 12 can conveniently be employed for stacking, in implant transportation operations or for storage purposes, a plurality of pieces of ware such as 13 without their complementing covers such as 14.

I claim:

1. As an article of manufacture, a resilient packaging protector comprising a divider member for a bowllike piece of ware having generally upright sidewalls terminating in the usual rim and a complementing cover having a normally depending and annular low wall portion and a flange portion extending outwardly from such wall portion, such ware and associated cover to be packed in a carton with said cover in an inverted nesting attitude within the upper region of the interior of said piece of ware and with sidewalls of said carton bounding said ware and its associated cover, said divider member including:
  - A. a flat relatively thin and narrow annular main member having,
    - I. a planar configuration corresponding to that of said rim of said piece of ware,
    - II. a lower surface for disposal adjacent the upper surface of said rim, and
    - III. an upper surface for receipt adjacent thereto of the normally upper surface of said annular flange portion of said cover;
  - B. a relatively thin wall depending from the inner periphery of said annular main member and having,
    - I. an outer surface for disposal adjacent the inner peripheral surface of said rim of said piece of ware, and
    - II. an inner surface for receipt adjacent thereto of the outer peripheral surface of said wall portion of said cover; and
  - C. a plurality of generally hollow impact-absorbing or cushioning tab portions extending outwardly from the outer periphery of said annular main portion of said divider member, each such tab portion having,
    - I. a relatively thin outer wall having an outer surface for disposal adjacent the inner surface of one of said sidewalls of said carton,
    - II. a relatively thin inner and upper wall having an outside surface conforming to a part of the outer peripheral surface of said flange portion of said cover and for disposal adjacent such portion of such peripheral surface, and
    - III. a relatively thin inner and lower wall having an outside surface conforming to a portion of the outer peripheral surface of said rim of said piece of ware and for disposal adjacent such portion of such peripheral surface.
2. A packaging protector as in claim 1 and in which said divider member is formed of an elastomeric material.
3. A packaging protector as in claim 1 and in which said divider member is formed of polyethylene.
4. A packaging protector as in claim 1 and in which said plurality of tab portions comprise first and second diametrically opposite pairs of such portions.
5. A packaging protector as in claim 1 and in which said outside surface of said inner and lower wall of each said tab portion of said divider member and an associated portion of said outer surface of said depending wall of the divider member define boundaries of a channel for receipt therein of a portion of said rim of said piece of ware in a snug relationship with said surfaces.
6. A packaging protector as in claim 5 and in which said divider member is formed of an elastomeric material.

7. A packaging protector as in claim 5 and in which said divider member is formed of polyethylene.

8. A packaging protector as in claim 1 and in which each respective said part of said outer peripheral surface of said flange portion of said cover contacts, in a snug relationship therewith, said conforming outer surface of said inner and upper wall of each respective said tab portion of said divider

member.

9. A packaging protector as in claim 8 and in which said divider member is formed of an elastomeric material.

10. A packaging protector as in claim 8 and in which said divider member is formed of polyethylene.
